GAS MIXER

Frank J. Hamrock and Elmer L. Simonson,
Homestead, Pa.

Application August 13, 1938, Serial No. 224,782

3 Claims. (Cl. 48—180)

The device forming the subject matter of this application is adapted to be mounted in the fuel line of an internal combustion engine, to the end that the fuel may be broken up and vaporized. 5 One object of the invention is to supply an article of the class described which may be adapted readily to fuel conduits of different internal diameters.

A further object of the invention is to supply 10 a device of the sort referred to, which may be made without the usual base plate which lies between the outstanding flanges of the parts of a fuel conduit. The invention aims, further, to supply a construction which is peculiarly efficient 15 in breaking up and vaporizing the fuel.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment 25 of the invention herein disclosed, may be made within the scope of what is claimed, without departing from the spirit of the invention.

In the accompanying drawing:

30 Fig. 1 is a longitudinal section on the line 1—1 of Fig. 3, parts remaining in elevation;

Fig. 2 is a longitudinal section in a plane at right angles to the cutting plane in Fig. 1;

Fig. 3 is a section on the line 3—3 of Fig. 1;

35 Fig. 4 is a section on the line 4—4 of Fig. 2.

The device forming the subject matter of this application is adapted to be used anywhere in the fuel line of an internal combustion engine. In Figs. 1 and 2, the numeral 1 designates conduit members having outstanding flanges 2. A gasket 3 is interposed between the flanges 2, and the flanges 2 are clamped on the gasket 3 by securing elements 4. The end of the conduit 1—1 which is disposed toward the carburetor is marked by the numeral 5, and the end which is disposed toward the intake manifold is marked by the numeral 6.

The article forming the basis of the present application preferably is made of metal throughout. It comprises curved side walls 20, which are spaced apart, circumferentially, at their longitudinal edges, as shown at 21. The side walls 20 have, each, an outwardly extended flange 22.

The side walls 20 are bendable throughout their 55 entire width, and they are bendable, also, at

places 23 where they are joined, integrally, to the outer edges of radial, plate-like fins 17. Owing to the construction last above referred to, the side walls 20 may be so shaped, by bending, as to conform to the bore 21 of any fuel conduit, and it is not necessary to provide a plurality of devices of the class described, in order to fit fuel conduits of different internal diameters, an observation which will be appreciated readily when Fig. 4 of the drawing is noted.

The radial, plate-like fins 17 have tapered, curved-ended tips 18, which have a circumferential inclination. The tips 18 are supplied with any desired number of perforations 19. At their inner ends, the fins 17 have curved arms 50, 15 provided with outstanding radial fingers 51. The finger 51 on the arm 50 of each fin 17 is attached to the next adjoining fin 17 by securing elements 52. The curved arms 50 cooperate to form a tubular socket 53.

In the socket 53 is located a tubular axial bearing 7, comprising a body 54 and a foot ring 8. The body 54 has a reduced end, threaded into the foot ring 8. Through the foot ring 8, through the reduced end of the body 54 and through the socket 53 is extended a securing element 68, which may be a rivet. The bearing 7 has a double-diametered bore defining a shoulder. In the body 54 of the bearing 7, a shaft is journaled, the shaft including a main member 10 having a reduced end 11, the parts 10 and 11 defining a shoulder 12 which cooperates with the shoulder of the bearing 7 to prevent the shaft 10—11 from moving endwise in one direction. Endwise movement of the shaft 10—11 in an opposite direction is prevented, and the shaft is anti-frictionally supported for rotation, by a single ball 9 which is interposed between the end of the main member 10 of the shaft 10—11 and the securing element 68.

A rotor is provided, and includes any desired number of blades 14, two oppositely disposed blades being shown, although the invention is not limited to the use of two blades. The blades 14 have a suitable pitch, as indicated in the drawing. The hub that connects the blades 14 is secured at 15, in any desired way, to the part 11 of the shaft 10—11. There are openings 16 in the blades 14, the openings preferably being of fairly good size, and being located adjacent to the outer ends of the blades.

It is to be observed that the device has no continuous base, constructed in general outline like the flanges 2 of the conduit members. The securing devices 4 do not pass through any portion 55

- of the structure forming the subject matter of this application, the flanges 22 simply being bound between the gasket 3 and one of the flanges 2, as shown in Fig. 1. The gasket 3 is the ordinary gasket used in making a tight joint in the fuel conduit, and no other or additional gaskets are required. The flanges 22 are seated in the standard gasket 3, as shown in Fig. 2, when the securing elements 4 are tightened up.
- 10 The operation of the structure so far as breaking up the fuel and vaporizing it are concerned, will be understood readily from the drawing. The article may be turned out, as to the walls 20, the fins 17 and the flanges 22, in a single operation.
- 15 The device shown produces a snappy engine operation, a saving of fuel, a quick pick-up, increased power, a minimum carbon monoxide production, and there will be little carbon accumulation.
- 20 Having thus described the invention, what is claimed is:
1. A gas mixer of the class described, including a central bearing, substantially radial mixing fins, means for securing the inner ends of the fins to the bearing, and circumferentially extended walls each joined along one edge to the outer edge of one of the fins, the opposite edges of the walls being free throughout their entire length, the walls being bendable throughout their entire width to different curvatures, thereby to adapt the mixer to fuel conduits of different diameters, transversely-spaced means carried by the walls and movable relatively to each other

when the walls are bent as aforesaid, for anchoring the mixer in a fuel conduit.

2. A gas mixer of the class described, including a central bearing, substantial radial mixing fins, means for securing the inner ends of the fins to the bearing, and circumferentially extended walls each joined along one edge to the outer edge of one of the fins, the opposite edges of the walls being free throughout their entire length, the walls being bendable throughout their entire width to different curvatures, thereby to adapt one mixer to fuel conduits of different diameters, the walls having transversely spaced outwardly extended anchoring flanges movable relatively to each other when the walls are bent as aforesaid, for holding the mixer in a fuel conduit.

3. A gas mixer of the class described including a socket having substantially radial mixing fins and circumferentially extended walls each joined along one edge to the outer edge of one of the fins, the opposite edges of the walls being free, the walls being bendable to different curvatures, thereby to adapt one mixer to fuel conduits of different diameters, means for anchoring the mixer in a fuel conduit, a bearing in the socket, the bearing comprising a body and a foot ring detachably connected thereto, a securing element connecting the body and the foot ring of the bearing and mounted in the socket, a spinner including a shaft journaled in the body of the bearing, and a single ball interposed between one end of the shaft and the securing element.
